PACKAGED PIECE GOODS

Irving J. Mishkin, New York, N. Y., assignor to
The Lampert Company, Inc., New York, N. Y.

Application January 6, 1949, Serial No. 69,470

4 Claims. (Cl. 206—46)

1

This invention relates to new and useful improvements in goods packaging, and, more particularly, the aim is to provide a novel and valuable packaging of textile piece goods.

The cardinal object of the invention is to provide an improved packaging for a definite, specific article of merchandise, and yet one which like a cloth remnant may vary in areal or length characteristic, and wherein, in addition to providing a protective and preferably a transparent envelope, this latter for adequately displaying the merchandise, the packaging is effected in a manner to prevent the direct fingering and possible soiling of all but an inconsequential portion of the packaged article, and at the same time in a manner to project the last-named portion of the article beyond the sealed portion of the package and at a location such that said portion may be given a close and wholly satisfactory visual and tactile examination for determination of texture and quality.

The present invention is to be sharply distinguished from previous proposals for the display of merchandise characterized merely by expedients to add visually to the sales appeal and/or to add to the sales appeal by some actual or allegedly unique exposure of the entirety or a part of the article and/or by an artistic effect sought to be attained by a special draping, fluffing or other arrangement of said article. Otherwise stated, these proposals have essentially been solely decorative or artistic, rather than utilitarian, or, if utilitarian in any sense, merely such from the standpoint of better or more attention striking visual display.

Another feature of the present invention whereby it differs radically from the prior suggestions referred to is that the latter all have to do with articles fabricated to a norm, with each of such articles packaged as a unit exactly like all its fellows. For example, articles in the class of hair-nets, handkerchiefs, neckties or goods such as gloves or stockings are normally sold as packaged units.

On the other hand, the present invention has to do with articles, i. e., textile piece goods, which normally are not sold by the unit, but, instead, are normally sold either as a full-length piece, in bolt form, and ranging usually in length from 40 yards up to 120 yards and even longer, or as specially cut off lengths from such bolt particularly specified by the particular customer at the time of retail sale. Ordinarily, the bolt of cloth, as bought by a garment manufacturer, is used in the making of garments for sale; and if the bolt of

2

cloth is bought by a department store owner or other shopkeeper it is for stocking his shelves so that a salesperson may cut from the bolt such length of the cloth as may be required by a customer.

These lengths of 40 yards and up are usually laid out full length and folded a number of times to form a bolt of cloth, and this is the put up generally preferred by manufacturers. Retailers frequently require more convenient put ups, in which case the goods are folded along the length to half width, and then rolled; a process known as doubling and rolling. Here, because of the double thickness of the cloth, the pieces usually run in length between 30 and 40 yards.

Shorter pieces than those last-mentioned are generally understood in the trade to have somewhat lesser value, and when under 10 yards in length are spoken of as remnants or fall-offs.

These remnants result from small lengths remaining in the course of manufacture and processing of the cloth, or sometimes from cutting out a longer length a portion of which is defective or below standard.

So far as I am aware there heretofore has been no attempt to prepare short pieces of textile material, each of a precise length, and so adapted for a particular purpose to be anticipated to be later in the mind of a particular retail customer, and to prepare a plurality of such pieces some or all differing in areal expanse or lengthwise dimension, and to package each of these short pieces in a special way, or, indeed, in any way.

But by the packaging of the present invention, there is presented a piece of goods prepared, processed and finished as are other types of full-length piece-goods, and cut into a specified length which is the length commonly required for the making at home of a particular article of clothing, as a dress. Furthermore, by the packaging of the present invention, said dress length is complete and personalized to the extent that the customer can select it and carry it home in its packaged condition. Moreover, the new package, while fully protecting each short length of piece goods from dust and damage from miscellaneous handling at the retail establishment, is so constituted, as already pointed out, that a portion of the cloth, as a corner thereof, is exposed, so that the purchaser can feel the texture and finish of the cloth as well as note the appearance thereof without the intervention of any supposedly transparent covering.

For further comprehension of the invention, and of the objects and advantages thereof, ref-

erence will be had to the following description and accompanying drawings, and to the appended claims in which the various novel features of the invention are more particularly set forth.

In the accompanying drawings forming a material part of this disclosure:

Fig. 1 is a perspective view showing a now favored way of packaging a piece of textile material pursuant to the invention.

Fig. 2 is a similar view, but partially broken away and partially in section, showing a now favored form of transparent envelope structure for providing the finally established package, with the open end thereof illustrated as in course of being folded over after there has been inserted into said envelope a piece of textile material folded and arranged pursuant to the invention.

Fig. 3 is also a perspective view, this showing said piece of textile material as partially folded, with various portions thereof lifted somewhat for clarity of explanation.

Fig. 4 is a top plan view of said piece of textile material, as preparatorily first folded into a plurality of plies and as then given a first subsequent fold, the latter shown by way of example as a lengthwise fold to reduce the stack of said plies to half width; a stiffener insert, as a sheet of ordinary cardboard, being here shown in a convenient placement of the same, so as ultimately to have such sheet disposed as in Fig. 3.

Fig. 5 is an end elevation of the arrangement shown in Fig. 4, looking toward the right in the latter view.

Fig. 6 is a side elevation of said arrangement, looking upward in Fig. 4.

Fig. 7 is a somewhat enlarged detail perspective view, fragmentarily showing the completed package of Fig. 1.

In the drawings, relative thicknesses are exaggerated at various places, particularly in Figs. 5 and 6.

The piece of goods 10 to be packaged pursuant to the invention, as in an envelope 12, which latter is desirably made of a very thin, pliant and transparent material such as glassine, cellophane, pliofilm or the like, may be variously folded, and with all of such folds similarly extended or with some extended angularly relative to another or others, as best suited to the dimensions of said envelope or an equivalent and the dimensional characteristics of said piece 10, to provide, preferably, a plural-ply slab-like compacting of said piece.

As indicated in Figs. 3-6, the piece 10 is shown, by way of example, as variously folded to establish first a main stack 14 of plies of the goods; and then this main stack is folded along the two lines 15 and 16 to swing in toward each other longitudinal side portions of the stack 14, to reduce the width of the stack and substantially all over the same to double the plurality of plies present along opposite sides of a central slender portion 17.

Now the provision of the already mentioned corner portion of the piece 10 to be finally protruded as at 18 in Fig. 1 is prepared for; and also, if the already mentioned cardboard stiffener or equivalent is to be included in the package, the same, indicated at 19, is had ready at hand, for being at this time placed as shown in Fig. 4 or for insertion into the goods piece 10 at some other convenient point in the further folding of said piece 10.

With the piece 10 folded to the extent indicated in Figs. 4-6, a portion of a top ply, as the top ply

over which in Fig. 4 the cardboard sheet 19 is illustrated as superposed, is diagonally folded, as along the line 20, thereby to project said corner portion 18 as shown in full lines in Figs. 3, 4, and 6 and as indicated in dot and dash lines at 18^a in Fig. 3. The edge 21 is illustrated as pimpled, to minimize unravelling and to facilitate close examination of the quality of the goods by an intending purchaser.

Next, and to produce from the set up of Fig. 4 the set up of Fig. 3, the former set up is folded in half along the line *a* in the direction of the arrow A, see Fig. 5, then along the line *b* in the direction of the arrow B, see Fig. 6, and then along the line *c* in the direction of the arrow C.

With the corner portion 18 in its 18^a location in Fig. 3, the final folding is along the line *d* in the direction of the arrow D, see Fig. 6.

The envelope 12 may be of any desired construction, but as here shown the same is conventionally illustrated as comprising two blanks 22 and 23, the former of elongate rectangular outline, and the latter having a main central portion of like outline, but with this subtended along three sides by strip-flaps 24, these last folded over onto the sheet 22 and suitably secured thereto, as by an adhesive.

The goods piece 10, folded as in Fig. 3 and then further folded as explained in connection with the fold line *d*, is inserted, with its side marked by said fold line foremost, all the way into the envelope 12. At the conclusion of this insertion, the "sampling" corner portion 18 is projected beyond the open mouth 25 of the envelope. The last step, to complete the packaging, is to fold the envelope 12 along the line 26, the location of this line being determined by the location in the envelope of the side of the folded piece 10 opposite to its side marked by said fold line *d*, and suitably, as by an adhesive, to secure the thus folded over portion 27 of the envelope to the remaining body thereof; and so dispose the parts as shown in Figs. 1 and 7. The adhesive last-named may comprise two or more spots thereof, as indicated at 28.

Where the piece goods is patterned, and has a right side, or its pattern is added by imprinting, the piece 10 desirably will be folded to have the side thereof which is imprinted or which is otherwise its right side outwardly facing behind the two faces of the envelope 12; and the folded piece 10 will also, preferably, be so placed in the envelope that the swatch-like corner portion 18 will have its right side the side thereof which is adjacent to the observer of Figs. 1 and 7.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A package for a folded piece of textile material having a single ply corner portion extending laterally from between the folds at one side thereof, comprising an envelope enclosing the folded piece of textile material and having a mouth opening along one side thereof, the folded piece of material being positioned in said envelope with its corner portion at the mouth opening, said envelope at said mouth opening having adjacent parallel co-extensive edge portions be-

yond the free edges of which the corner portion of the folded piece of material projects when the folded piece of textile material is positioned completely in said envelope.

2. A package for a folded piece of textile material having a single ply corner portion extending laterally from between the folds at one side thereof, comprising an envelope enclosing the folded piece of textile material and having a mouth opening along one side thereof, the folded piece of material being positioned in said envelope with its corner portion at the mouth opening, said envelope at said mouth opening having adjacent parallel co-extensive edge portions beyond the free edges of which the corner portion of the folded piece of material projects when the folded piece of textile material is positioned completely in said envelope, and means sealing said edge portions with the extremity of said corner portion projected beyond the free edges of said edge portions.

3. A package for a folded piece of textile material having a single ply corner portion extending laterally from between the folds at one side thereof, comprising an envelope enclosing the folded piece of textile material and having a mouth opening along one side thereof, the folded piece of material being positioned in said envelope with its corner portion at the mouth opening, said envelope at said mouth opening having adjacent parallel co-extensive edge portions beyond the free edges of which the corner portion of the folded piece of material projects when the folded piece of textile material is positioned completely in said envelope, said edge portions being folded over onto one side of the main portion of the envelope for closing said mouth opening with the extremity of said corner portion projecting beyond the free edges of said edge portions, and means securing said edge portions to

one another and to the said one side of said envelope.

4. A package for a folded piece of textile material having a single ply corner portion extending laterally from between the folds at one side thereof, comprising an envelope enclosing the folded piece of textile material and having a mouth opening along one side thereof, the folded piece of material being positioned in said envelope with its corner portion at the mouth opening, said envelope at said mouth opening having adjacent parallel co-extensive edge portions beyond the free edges of which the corner portion of the folded piece of material projects when the folded piece of textile material is positioned completely in said envelope, said edge portions being folded over onto one side of the main portion of the envelope for closing said mouth opening with the extremity of said corner portion projecting beyond the free edges of said edge portions, and means securing said edge portions to one another and to the said one side of said envelope, said securing means comprising spots of adhesive between the adjacent faces of said edge portions at the sides of said corner portion and between the said one side of said envelope and the adjacent edge portion.
